US0D1059601S

(12) **United States Design Patent** (10) Patent No.: **US D1,059,601 S**
(45) Date of Patent: ** Jan. 28, 2025

(54) **ADHESIVE BANDAGE WITH DECORATED PAD**

(71) Applicant: **Johnson & Johnson Consumer Inc.**, Skillman, NJ (US)

(72) Inventors: **Leonardo Caneppele**, São José dos Campos (BR); **Andre Narcizo**, São José dos Campos (BR); **Paulo Cesar de Godoy Oriani**, São José dos Campos (BR); **Carmine Rizzo**, Port St. Lucie, FL (US); **Andre Luiz Santos**, São José dos Campos (BR)

(73) Assignee: **Kenvue Brands LLC**, Summit, NJ (US)

(**) Term: **15 Years**

(21) Appl. No.: **29/776,246**

(22) Filed: **Mar. 29, 2021**

(56)

CLAIM

The ornamental design for an adhesive bandage with decorated pad as shown and described.

DESCRIPTION

FIG. 1 is a top perspective view of a first embodiment of the present invention;
FIG. 2 is a top view of the adhesive bandage with decorated pad depicted in FIG. 1;
FIG. 3 is a left side view of the adhesive bandage with decorated pad depicted in FIG. 1;
FIG. 4 is a bottom view of the adhesive bandage with decorated pad depicted in FIG. 1;
FIG. 5 is a right side view of the adhesive bandage with decorated pad depicted in FIG. 1;

FIG. 6 is a front side view of the adhesive bandage with decorated pad depicted in FIG. 1;
FIG. 7 is a back side view of the adhesive bandage with decorated pad depicted in FIG. 1;
FIG. 8 is a top perspective view of a second embodiment of the present invention;
FIG. 9 is a top view of the adhesive bandage with decorated pad depicted in FIG. 8;
FIG. 10 is a left side view of the adhesive bandage with decorated pad depicted in FIG. 8;
FIG. 11 is a bottom view of the adhesive bandage with decorated pad depicted in FIG. 8;
FIG. 12 is a right side view of the adhesive bandage with decorated pad depicted in FIG. 8;
FIG. 13 is a front side view of the adhesive bandage with decorated pad depicted in FIG. 8; and,
FIG. 14 is a back side view of the adhesive bandage with decorated pad depicted in FIG. 8.
